UNITED STATES PATENT OFFICE.

CHARLES EDWARD HAVILAND, OF LIMOGES, FRANCE.

DESIGN FOR A PLATE OR DISH.

SPECIFICATION forming part of Design No. 28,926, dated June 28, 1898.

Application filed June 1, 1898. Serial No. 682,301. Term of patent 7 years.

To all whom it may concern:

Be it known that I, CHARLES EDWARD HAVILAND, a citizen of the United States, residing at the city of Limoges, in the Republic of France, have invented and produced a new and original Design for a Plate or Dish or Similar Article, of which the following is a specification, reference being had to the accompanying drawings, forming part thereof, and in which—

Figure 1 is a top view of a plate or dish bearing and incorporating my design, and Fig. 2 is a vertical transverse section of same on the dotted line 2 2 of Fig. 1.

The leading feature of my design consists of the ornamentation along the rim of the plate or dish, substantially as shown in the accompanying drawings.

In the drawings, A denotes the rim of the plate or dish, whose outer edge bears the ornamental band arranged on a scalloped plan and comprising the outer field B, the inner alternate long and short scroll figures lettered, respectively, C D, and the scroll-figures E, connecting the figures CD at their center with the said outer field B, as shown.

What I claim is—

The design for a plate or dish or similar article, substantially as shown and described.

Signed at New York, in the county and State of New York, this 31st day of May, A. D. 1898.

CHARLES EDWARD HAVILAND.
